PRESSURE INDICATOR

Michel Kadenacy, Paris, France, assignor of one-half to Armstrong Whitworth Securities Company, Limited, London, England

Application June 1, 1936, Serial No. 82,958
In Great Britain January 11, 1936

4 Claims. (Cl. 73—51)

The present invention relates to pressure indicating devices and more particularly to devices of the kind which are suitable for giving indications of fluid pressures which vary rapidly between wide limits as a function of time and in which the said variations are repeated at uniform intervals, as occurs for example in the cylinder and in the inlet and exhaust ducts of internal combustion engines.

10 The object of the invention is to provide a device of the above kind, which is capable of giving reliable indications of pressures free from inaccuracies which might be occasioned by the rapidity at which the indication of pressure must be obtained.

The invention consists in a pressure indicating device for an internal combustion engine including pressure sensitive indicating means for registering variations in pressure above and below atmospheric pressure, and variations in the velocity and direction of movement of fluids in the inlet and exhaust conduits of the engine, a member having ports connected to the pressure sensitive indicating means, a complementary member having ports co-operating with the first mentioned ports, ducts extending in opposite directions with respect to the axis of the conduit and connecting said second mentioned ports to the source of pressure, a shutter element relatively 25 rotatable with respect to said members and having ports co-operating with the ports in the members to connect the source of pressure to the indicating means and means to produce said relative rotation whereby the indicating means 30 are connected to the source of pressure at recurring intervals of time.

The pressure indicating device according to the invention is very suitable for indicating the wide and rapid changes from a high pressure to a practical vacuum that occur in the cylinder and in the exhaust and inlet ducts of an internal combustion engine during its operation, and is particularly useful in enabling the movements of the exhaust and inlet gases to be examined, especially when it is desired to determine when the gases leave the cylinder as a mass, consequent upon the opening of the exhaust orifice, at a speed higher than that obtaining when an adiabatic flow only is involved and in such a short interval of time that they are discharged wholly or substantially wholly from the cylinder, leaving a high degree of vacuum behind them and when the return of these gases occurs, for the purpose of establishing a timing of inlet suitable for utilizing the intervening depression when charging

the cylinder, and for the purpose of revealing any corrections that require to be made in the timing and arrangement of the engine.

One example of a convenient embodiment of the invention suitable for use in examining the pressure variations and the movement of the gases in the exhaust or inlet duct of an internal combustion engine will now be described by way of example only, without limitation to this particular use, and with reference to the accompanying drawing, in which:

Figure 1 shows an axial section through the device.

Figure 2 is a section taken on the line x—x in Figure 1.

In the example illustrated in the drawing, the device comprises a sleeve formed of two concentric tubular elements 1, 2 between which is situated a rotatable ported shutter 3, carrying a sprocket wheel 4 for permitting the shutter to be driven by any suitable means, for example from the crank shaft of the engine.

This sleeve 1, 2 is open at both ends and is mounted with freedom for angular movement in end supports 5 in the form of rings adapted to be connected rigidly by means of flanges 6 within the inlet or exhaust duct of an internal combustion engine.

The outer sleeve element 2 has a pair of ports 7, 8 for connection through suitable unions 9, 10 with two pressure sensitive indicators such as water or mercury manometers 23, 24 capable of indicating all pressures from approximately zero absolute to the highest pressure encountered, and the inner sleeve member 1 has two corresponding ports 11, 12 connected with short tubular ducts 13, 14 extending into the interior of the sleeve and having their outlet ends facing in opposite directions along the axis of the sleeve.

The rotary shutter 3 also has a pair of ports 15, 16 co-operating with the ports in the sleeve so as to establish and cut off communication between the interior of the duct and the pressure sensitive means intermittently during its rotation.

One of the fixed end pieces 5 supporting the sleeve carries a scale 17, and the sleeve carries a pointer 18 moving over the scale 17 and is provided with an adjusting lever 19, whereby the sleeve can be moved through any required angle as and when desired for the purpose of varying the moment at which the ports in the sleeve and shutter coincide during the rotation of the shutter.

The sleeve also comprises suitable water pas-

sages 20 for connection to a supply of cooling water through the connections 21 and 22.

When such a device is employed for obtaining indications of pressure in the inlet or exhaust duct of an internal combustion engine, and the shutter is driven in synchronism with the rotation of the crankshaft, each time the ports in the shutter and sleeve coincide a pressure impulse will be transmitted to the pressure indicating means and will give a reading of pressure for a determined crank angle, and this reading will not be due to one single impulse but to a series of impulses succeeding each other with a rapidity depending upon the engine speed. Consequently the reading may be continued at this point until a stable indication substantially free from fluctuations has been obtained and then by varying the angular adjustment of the stationary sleeve, readings at any desired angular intervals of crank angles may be obtained in succession with a high degree of accuracy.

Further, according to the direction of movement of the fluid in the conduit, different pressure readings will be obtained from the two ports on the sleeve and these differences in pressure will enable the speed and direction of movement of the fluid to be determined.

Records of the changes in pressure occurring in the exhaust duct of an internal combustion engine taken with a device such as that described above show clearly the period of delay that occurs before the gases leave the cylinder, the abrupt rise in pressure due to the mass exit of the gases; the immediately following abrupt fall to a high degree of vacuum when the mass has passed beyond the pressure indicator, and the subsequent rise in pressure, due to the return of the gases.

A device such as that described is suitable for use on an internal combustion engine during the exhaust and admission phases, for registering static and dynamic pressures with a simultaneous indication of the directions and of the intensity of the gaseous currents, in order to detect the fluctuations, the speeds, the pressures and the mass movements of the gases in the admission duct, the exhaust duct and the cylinder.

I claim:

1. A pressure indicating device for an internal combustion engine including pressure sensitive indicating means for registering variations in pressure above and below atmospheric pressure, and variations in the velocity and direction of movement of fluids in the inlet and exhaust conduits of the engine, a member having ports connected to the pressure sensitive indicating means, a complementary member having ports co-operating with the first mentioned ports, ducts extending in opposite directions with respect to the axis of the conduit and connecting said second mentioned ports to the source of pressure, a shutter element relatively rotatable with respect to said members and having ports co-operating with the ports in the members to connect the source of pressure to the indicating means and means to produce said relative rotation whereby the indicating means are connected to the source of pressure at recurring intervals of time.

2. A pressure indicating device for an internal combustion engine including pressure sensitive indicating means for registering variations in pressure above and below atmospheric pressure and variations in the velocity and direction of movement of fluids in the inlet and exhaust conduits of the engine, a sleeve element having ports connected to the pressure sensitive indicating means, a complementary sleeve element having ports co-operating with the first mentioned ports, ducts extending in opposite directions with respect to the axis of the conduit and connecting said second mentioned ports to the source of pressure, a shutter element relatively rotatable with respect to said sleeve elements and having ports co-operating with the ports in said elements to connect the source of pressure to the indicating means, and means to produce said relative rotation whereby the indicating means are connected to the source of pressure at recurring intervals of time.

3. A pressure indicating device as claimed in claim 2, including a fixed member supporting said sleeve elements with freedom for angular movement and an adjusting member on said sleeve elements to permit the sleeve elements to be moved through any desired angle for the purpose of varying the moment at which the ports in the sleeves and shutter coincide.

4. A pressure indicating device for an internal combustion engine including pressure sensitive indicating means for registering variations in pressure above and below atmospheric pressure and variations in the velocity and direction of movement of fluids in the inlet and exhaust conduits of the engine, a sleeve element having ports connected to the pressure sensitive indicating means and having a hollow wall, a complementary sleeve element having ports co-operating with the first mentioned ports and having a hollow wall, ducts extending in opposite directions with respect to the axis of the conduit and connecting said second mentioned ports to the source of pressure, a shutter element relatively rotatable with respect to said sleeve elements and having ports co-operating with the ports in said elements to connect the source of pressure to the indicating means, means to circulate cooling fluid through said hollow walls of said sleeve elements, and means to produce said relative rotation whereby the indicating means are connected to the source of pressure at recurring intervals of time.

MICHEL KADENACY.
